**TOOL FOR REMOVING DOWEL WASHERS
FROM THE DOWEL**
Karoly Kovacs, 3514 S. Laramie Ave.,
Cicero, Ill. 60650
Filed Oct. 31, 1966, Ser. No. 590,964
3 Claims. (Cl. 29—239)

ABSTRACT OF THE DISCLOSURE

A tool for removing a split dowel washer from a dowel, which tool has a pair of members movable with respect to each other, with each member having a handle portion and a jaw member with the jaw shaped complementary to the dowel washer and with one of the jaw members having a rib to engage the split in the dowel washer to spread the washer for removal from the dowel.

This invention relates to a tool for use in removing dowel washers from the dowel.

One of the objects of this invention is to provide a tool for use in easily and readily removing a dowel washer from a dowel.

Dowel washers are used in connection with dowels in retaining the hub secured to the ring plate. The hub carries the axle. In use the dowel washers become wedged to the dowel so that it is difficult and at times impossible to remove the dowel washer when it is desired to remove the hub and axle. This is eliminated by the present invention in that the tool is applied to the dowel washer to firmly engage it and to readily remove the dowel washer.

This invention may be used for removing dowel washers from dowels wherever used.

Other objects will become apparent as this description progresses.

In the drawings:

FIGURE 1 is a perspective view of the tool forming 40 this invention.

FIGURE 2 is an enlarged view showing the jaws of the tool in a reversed position from that of FIGURE 1.

FIGURE 3 is a view of the dowel and the dowel washer which the tool is to operate on.

FIGURE 4 is a sectional view showing the dowel and the dowel washer connected to the part from which it is to be removed.

FIGURE 5 is a view partly in section showing the jaws of the tool applied to the dowel washer when removing 50 the dowel washer.

FIGURE 6 is a view taken on line 6—6 of FIGURE 5.

FIGURE 7 is a view taken on line 7—7 of FIGURE 5 but showing the position of the jaws before it engages the dowel washer, and

FIGURE 8 is a view taken on line 8—8 of FIGURE 5 but showing the jaws in fully clamped position.

The tool forming this invention is generally indicated at 10 and comprises a pair of members generally indicated at 12 and 14 connected together by a pin 16 to operate in much the same manner as a plier. The member 12 has a handle portion 18, an intermediate body portion 20 and a jaw 28, all integrally formed. The member 14 has a handle portion 24, an intermediate portion 26 and a jaw 22. The intermediate body portions 20 and 26 are each approximately one-half the width of the member so that they are positioned adjacent each other and the pin 16 connects or joins the two members together. The foregoing structure is conventional to pliers and like tools.

The invention here resides in the shape and construction of the jaw members generally indicated at 22 and

2

28. The jaw member 28 has a rear section which has a partial cylindrical shaped surface 30. The jaw continues forwardly and the front or mouth portion of the jaw is recessed to provide a stepped configuration comprising a vertical end wall 32 and a conical tapered recessed surface 34 which conforms to the exterior shape of the dowel washer to be described.

The other jaw member 22 is shaped similarly to the jaw 28 just described and has a rear section which has a partial cylindrical shaped surface 36 and a front or mouth portion provided with a vertical end wall 38 and a conical tapered recessed surface 40. The jaw 22 has a longitudinally extending slot 42 which receives a rib or wedge member 44 which extends into the mouth of the jaw. The rib or wedge element 44 is anchored to the jaw 22 by pins 45. The rib or wedge member extends the full length of the mouth and partially into the rear section of the jaw. The exposed edge of the rib or wedge member 44 has tapered surfaces forming a knife-like edge 46.

One of the uses of the dowel and dowel washer shown here is in connection with an axle shaft and the means for connecting the hub of the axle shaft to the ring plate. As shown in FIGURE 4, the hub 50 has an axle shaft (not shown) affixed to it. The hub has spaced openings 52 which are conically tapered to receive the dowel washers generally indicated at 54 as well as the dowel or studs 56. The ring plate 58 has spaced openings 60 with which the openings 52 of the hub 50 are aligned. The dowel 56 is externally threaded at its opposite ends as at 61 and 62 but has an intermediate smooth surface as at 63.

The dowel is positioned in the aligned openings 52 and 60. A nut 64 is secured to the threaded end 62 of the dowel. The dowel washer 54 is a sleeve-like member having an inside smooth cylindrical surface 66 and an outside frusto-conical shaped surface or wall 68. The sleeve body of the dowel washer has a slot 70 which provides a split sleeve body. The dowel washer 54 is positioned on the dowel 56 with the dowel washer in engagement with the smooth surface 63 of the dowel. The dowel and dowel washer are then inserted into the conically tapered opening 52 in the hub 50 so that the dowel washer rests within the conical tapered opening 52. The dowel extends through the opening 60 in the ring plate 58 and is secured by the nut 64. The opposite end of the dowel extends exteriorly of the hub 50. A flat washer 72 is positioned on the dowel adjacent the dowel washer and a threaded nut 74 is secured to the dowel.

In usage the dowel washer becomes so fixed and secured to the dowel that it becomes difficult to remove the dowel washer from the dowel when the hub has to be detached from the ring plate. The dowel 56 cannot be removed since the inside threaded nut 64 is inaccessible. With the dowel washer 54 fixed to the dowel the hub 50 cannot be removed until the dowel washer is removed from the dowel. This, however, is readily accomplished with the tool of this invention. The exterior threaded nut 74 is unthreaded and removed from the dowel as is the flat washer 72. The ring plate 58 is hit with a sledge hammer to cause the axle shaft to move outwardly away from the hub 50 and then the axle shaft is pushed back to its initial position causing the dowel washer 54 to separate a little from the hub sufficiently to permit the front of the jaws of the tool to engage the dowel washer.

The rib or wedge element 44 in the jaw engages the slot 70 in the dowel washer 54 and manual pressure on the handles 18 and 24 will cause the rib to enter the slot 70 and enlarge the slot and thereby spread or enlarge the sleeve body sufficiently so that it loosens from the smooth portion 63 of the dowel 56. The front or mouth portions of the jaws are shaped complementary to the frusto-conical shape of the dowel washer so that they completely

engage the dowel washer, as shown in FIGURE 5. The outer end of the dowel washer seats against the vertical walls 32 and 38 of the jaws and the portions of the jaws grip the dowel washer with the rib or wedge member 44 entering the slot of the dowel washer. The threaded portion 61 of the dowel will extend into the rear portions 30 and 36 of the jaws but the rear portions of the jaws will not be in engagement therewith when the jaws are in clamping position, as can be seen in FIGURE 5.

With this firm interlock on the dowel washer and the dowel washer loosened from the dowel, the dowel washer may be readily removed from the dowel so that the hub 50 (an axle) can be removed from the dowel and ring plate 58. Thus, the tool provides a very simple, inexpensive and efficient method of removing dowel washers from the dowel.

While the invention has been described in connection with a dowel washer used for a hub and ring plate, it will be understood that it may be used in connection with dowel washers wherever used.

It will be understood that various changes and modifications may be made from the foregoing without departing from the spirit and scope of the appended claims.

What is claimed is:

1. A tool for removing a dowel washer which has a frusto-conical shaped outer surface and a split from a dowel when same has been fixed thereto through usage, said tool including a pair of members movable with respect to each other, each member having a handle portion and a jaw member, each jaw member having a front section and a rear section, with the front section having a conical tapered recessed surface and a vertical end wall

to engage the dowel washer and in which one of the jaw members has a rib to engage the split in the dowel washer to spread the dowel washer.

2. A structure defined in claim 1 in which the rear section of each jaw member has a partial cylindrical-shaped surface to accommodate the dowel which may extend thereto.

3. A tool for removing a split dowel washer from a dowel when same has been fixed thereto through usage, said tool including a pair of members movable with respect to each other, each member having a handle portion and a jaw member, each jaw member having a front section and a rear section, with the front section shaped complementary to the shape of the dowel washer to engage the dowel washer and in which one of the jaw members has a rib to engage the split in the dowel washer to spread the dowel washer, the rear section of each jaw member having a partial cylindrical-shaped surface to accommodate the dowel which may extend thereto, with said surfaces out of engagement with the dowel when the jaws are closed.
